John F. Bodine, of Williamstown, N. J.
assignor to self
Wm H. & J. Alfreds Bodine, of same place.
Letters Patent No. 1000 dated Aug. 3, 1858.

The Schedule referred to in these Letters Patent and making part of the same.

To all whom it may concern:

Be it known that I, John F. Bodine of Williamstown in the County of Camden and state of New Jersey, have invented a new and ornamental design for covers of jars, and I do hereby declare . . . that the following is a full, clear and exact description of the same, reference being had to the accompanying drawings forming a part of this specification, in which

Fig: 1. is an edge view of my ornamental design for a preserve jar cover.

Fig: 2. a plan of the same, and

Fig: 3. a vertical section of the same applied to a jar.

Similar letters of reference, in each of the several figs. indicate corresponding parts.

My invention consists in molding jar covers with an ornamental bead which rises from their upper surfaces at a point near their circumference, as herein specified and shown in the accompanying drawing. A represents the jar cover molded with the ornamental bead B, said bead rising from the upper surface of the cover, B being located near the outer edge of the same. The raised bead B, may be made to taper slightly and may be flattened or rounded off, on its upper edge. By thus molding glass jar covers with the bead B, a neat ornamental finish is given to the appearance of the same, as will be evident from the drawing. What I claim as my invention & desire to secure by Letters Patent, is The ornamental design for a preserving jar cover, herein described and shown.
